UNITED STATES PATENT OFFICE

OTTO P. CHERDRON AND CARL W. SCOTT, OF SALT LAKE CITY, UTAH

BUILDING CONSTRUCTION

Application filed September 1, 1931. Serial No. 560,622.

An object of this invention is to provide a satisfactory building construction which can be made up in sections in a shop and assembled on the job, which might be called buildings of a steel frame type with separate panels slid into it.

Another object is to provide a building construction which is light in weight, easily handled, shipped, stored, assembled and disassembled without loss, and inexpensive to manufacture, and which lends itself for mass production.

Another object is to provide a building construction which will be very strong and rigid for a given weight of material.

These and other objects, as will hereinafter appear, are accomplished by this invention which is fully described in the following specification and shown in the accompanying drawings, in which—

Figure 1 is a partial perspective view of a shed or building embodying the invention showing one vertical panel and its corresponding roof panel in place, and other panels left open;

Fig. 2 is an enlarged partial vertical section through these panels, and showing the intermediate studding and rafter construction;

Fig. 3 is an enlarged section on either of the lines 3 of Fig. 2 through the studding or rafter;

Fig. 4 is an enlarged horizontal section on the line 4 of Fig. 1 showing the corner studding or rafter;

Fig. 5 is an enlarged vertical section showing the method of securing the ridge member to the roof panels;

Fig. 6 is a partial perspective view of the lower end of a rafter, together with a driving clip for securing the roof panels in place to form a finish;

Fig. 7 is a horizontal section through a studding showing the method of hanging a door or a sash hinge thereon;

Fig. 8 is an enlarged horizontal section showing a preferred form of corner studding or corner rafter on the line 4 of Fig. 1;

Fig. 9 is a section through an edge of a

panel showing the metal spring-like covering for the panel; and

Fig. 10 is a partial perspective detail of a tie or spacing rod for spacing the various vertical frame members through the gusset plates to lend rigidity to the structure.

The embodiment illustrated comprises essentially a skeleton frame for a building made up of spaced paralleled studding and rafters, each rafter being in alignment with the studding supporting it, and so formed that vertical panel members may be inserted between adjacent studding after which roof panels may be inserted between adjacent rafters to thereby complete the sides and roof of the building.

The frame or skeleton of the building comprises a baseplate or sill 11 which is adapted to be secured to a suitable foundation 12 as by means of bolts 13. To this sill is secured a plurality of vertically extending studding 14, which is shown in enlarged cross section in Fig. 3. This studding is formed from sheet metal into a general I-shape with spaced central webs 14^a, an enlarged central bead 14^b, the opposite end having spaced flange members 14^c and 14^d, these flange members having inwardly turned lips 14^e. The webs 14^a are preferably pressed inwardly and spot-welded at 14^f at intervals to hold them in spaced relation, as shown, thereby forming a space 14^g for the reception of a gusset plate, as will later be described.

The flanges 14^c, 14^d are resilient, and together with the inwardly turned lips 14^e serve to grip an insulating member 15, which preferably consists of a sheet of insulating board, wallboard, or the like, which is covered by a sheet metal sheath 16, the opposing edges of the insulating member having grooves 17, 18, Fig. 9 which are adapted to register with the longitudinal inwardly turned lips 14^e, so as to be gripped thereby. To assist in this gripping action and to make a reasonably weatherproof joint, the inner end 16^a of the sheath 16 is made to project a little outwardly, as shown in Fig. 9, to form a spring clamp.

The bottom of the insulating panel 15 is likewise grooved to receive the inwardly turned lips 11^a of the sill 11. In assembling

the shed or building the sill 11 is first set in place and bolted down, after which the studding 14 are secured thereto and bolted to upwardly turned ears 11^b of the sill 11. The rafters 19 are then secured to the tops of the studding 14 by means of gusset plates 20 which are slid into the space 14^c and secured thereto by means of bolts 21. Similarly, a gusset plate connects the upper ends of the rafters. At the ridge is secured a ridge member 22 which closes the gap of the roof panels, and which is similarly formed of sheet metal. This ridge member is shown in more detail in Fig. 5, and comprises an inwardly turned lip 22^a at each side, as well as a spring-like portion 22^b, which passes inwardly between and engages the upper ends of roof panels 23, and is then held in place by a spring action, as indicated in dotted lines in Fig. 5. It will be understood that the engaging portions of the panels and studding and rafters may be varied to a considerable degree by different forms of gripping action to make a reasonably weatherproof connection.

With the studding and rafters thus assembled and in place, as shown in Fig. 1, they are held in the proper spaced relation by means of a tie rod 24 (see Figs. 2 and 10) at each side of the shed and at the roof ridge, these rods passing through openings 25 of the shape of a key slot in the gusset plates, the rods being inserted through the large end of the slot and having necked-in portions 24^a which engage the small portion of the key slot to prevent movement of the studding relative to the rod. These rods may be round, flat, or the like. Side panels 15 may then be slid down between two adjacent studding, these panels passing between flanges 14^c and 14^d, as shown in Fig. 3, and having horizontally disposed opposing notches or grooves, such as engage the inwardly turned lips 11^a of the baseplate. Thus, the vertical panels are not only locked in place, but are also tightly fitted to the studding and baseplate which support them so as to be reasonably weatherproof. It will be noted that the rafters are cut back to permit the panels to be slid into place from above. This construction permits of the building being erected with a minimum of labor.

The roof is then formed by similarly inserting a roof panel 23 which is assembled in substantially the same manner, the rafters 19 being substantial duplicates of studding 14. These roof panels likewise are provided with longitudinal grooves into which fit inwardly turned lips of the rafters 19 in the same way as that which was shown in Fig. 3 and described for the studding. Thus, each roof panel serves as a lock to prevent the removal of its vertical side panel. A small crack may be left between the vertical panel and its roof panel, and this may be closed by means of a suitable cement 26.

Both these panels may be formed with suitable ribs, such as 16^a and 23^a, on the vertical and roof panels, respectively. These ribs improve the appearance of the panels and serve to give them additional stiffness. These panels may be further stiffened and strengthened by cementing the insulating member 15 to its sheath 16, Fig. 9.

The roof panel is then retained in place by means of a drive clip 27 which extends around adjacent lower ends of the roof panels 23, and has two spaced narrow portions 27^a adapted to fit into spaced openings 19^a and 19^b in the rafter 19 Fig. 6. Friction of these driving clips is sufficient to hold the roof members in place, and to close the gap between the lower ends of the roof panels.

In Figs. 1 and 4 is shown a form of corner post 28, while Fig. 8 shows another and preferred form of corner post 29. A method of hinging a sash to the studding is shown in Fig. 7 in which one leaf 30 of a hinge is secured to the studding 14 as by spot-welding at 30^a and 30^b, the other leaf 31 being secured to the sash 32 which is thus shown as being adapted to be swung outwardly. A suitable cornice as 33 Fig. 1 may be mounted at the gables of the building to give it a finished appearance.

Thus it will be seen that a very simple and efficient form of shed construction is provided which can readily be assembled and disassembled without destruction of any of the material forming the same which lends itself to manufacture in quantities in a shop for erection complete in the field, and which at the same time can be economically manufactured and sold.

While we have shown and described but a few embodiments of our invention, it is to be understood that it is capable of many modifications. Changes, therefore, in the construction and arrangement may be made which do not depart from the spirit and scope of the invention as disclosed in the appended claims.

We claim:

1. In a building construction, a structural member formed from sheet metal bent upon itself to form a cross section of substantially an I shape, having at one end of its cross section a bead and at the other end of the cross section two opposing channels with continuous integral flanges to engage panels by gripping spring action.

2. In a building construction, a structural member formed from sheet metal bent upon itself to form a cross section of substantially an I shape, having at one end of the cross section two opposing channels with continuous integral flanges to engage panels by gripping spring action.

3. In a building construction, a structural member formed from sheet metal bent upon itself to form a cross section of substantially

an I form, having at one end of its cross section a bead and at the other end two opposing channels with continuous integral flanges to afford a corner construction to engage panels by gripping spring action.

5 4. In a building construction, a structural member formed from sheet metal bent upon itself to form a cross section of substantially an I form, having at one end of the cross section two opposing channels with continuous integral flanges to afford a corner construction to engage panels by gripping spring action.

5 5. In a building construction, studding as described in claim 1, having inwardly turned lips on each flange of the channel and vertical panels slideable in said channels and having grooves corresponding in cross section to the inwardly turned lips, whereby they are adapted to be secured in 20 said channels.

25 6. In a building construction, studding composed of formed metal having inwardly turned edges on each flange of the channel and vertical panels slideable in said channels and having grooves registering with the inwardly turned edges, whereby they are adapted to be secured, said panels having a covering of sheet metal overlying the portions having the grooves, one edge of 30 said covering being free to spring outwardly to lock said panel and studding together to make it substantially weather-proof.

7. In a building construction, a structural member as described in claim 1, a sill of channel shape formed of sheet metal having a continuous channel formed with integral flanged members, adapted to receive the bottom of said vertical panel.

40 8. In a building construction, metal studding, metal rafters secured thereto and in alignment therewith, gusset plates connecting each studding and rafter in alignment and tie rods extending through and between 45 said gusset plates and having notched portions engaging openings in the gusset plates to hold the same in place.

9. In a building construction, metal studding, metal rafters, said studding and rafters 50 being formed of sheet metal bent to form substantially an I shape, having spaced sheet metal portions forming the web and gusset plates secured between said spaced sheet metal portions for fastening the studding and rafters together.

55 10. In a building construction, metal studding, metal rafters, said studding and rafters being formed of sheet metal bent to form substantially an I shape, having spaced sheet metal in the web, gusset plates secured in said web for fastening the studding and rafters together and tie rods having reduced portions passing through key-hole slots in said gusset plates whereby the reduced portions of the tie rods may engage reduced

portions of the key-hole slots to lock the studding and rafter sections in spaced relation.

11. In a building construction, studding having channels adapted to receive vertical 70 panels, vertical panels adapted to be slid from the top into said channels, roof panels of the same spacing as the vertical panels, adapted to be slid into place between the rafters, said roof panels leaving a space at 75 the top and a ridge member having outwardly extending yieldable edges adapted to be sprung inwardly to permit the ridge member to be secured to said roof panels.

12. In a building construction, studding having channels adapted to receive vertical 80 panels, vertical panels adapted to be slid from the top into said channels, roof panels of the same spacing as the vertical panels adapted to be slid into place between the rafters, and a drive clip adapted to pass 85 around the lower adjacent edges of two adjacent roof panels and having ends engageable with the rafter therebetween for securing the roof panels in place.

13. In a building construction, studding having channels adapted to receive vertical 90 panels, vertical panels adapted to be slid from the top into said channels, roof panels of the same spacing as the vertical panels adapted to be slid into place between the rafters, and a drive clip adapted to pass 95 around the lower adjacent edges of two adjacent roof panels and having ends engageable with the rafter therebetween for securing 100 these roof panels in place, said clip serving also to fill the gap between the lower ends of the roof panels filling the space between the over-hanging ends of the roof panels below the lower end of the rafter.

14. In a building construction, studding, rafters as described in claim 1, roof panels adapted to be slidably secured between the rafters to form a substantially weather-proof roof and a drive clip adapted to pass 110 around the lower adjacent edges of two adjacent roof panels and having ends engageable with the rafter therebetween for securing the roof panels in place.

15. In a building construction, ribs formed by rigidly attaching together studding and rafters of the form described in claim 1, said ribs being erected as a skeleton and wall and roof panels adapted to be slid into said skeleton to close the opening between the 120 same to form a building structure.
